CONTROL CARD BLANK

Harry O. George, Vestal, and Thomas R. Skofte-
land, Endicott, N. Y., assignors to Interna-
tional Business Machines Corporation, New
York, N. Y., a corporation of New York

Application December 1, 1936, Serial No. 113,562

1 Claim. (Cl. 154—46)

This invention relates to control cards for statistical machines and various types of calculating machines, such as tabulating and record sorting machines. Records containing data in the form of perforations are run through the machines and the machines are caused to perform certain operations such as the sorting of the records, or the printing or accumulating of data contained on the records. The location of perforations arranged in columns or otherwise determines the value of the perforations and the machines are controlled in accordance with the location of the perforations.

Records for use in such machines must be carefully prepared so that the perforations are accurately located and the stock from which the records are made must be of unusually high grade in order that the control of the records upon the machines will be accurate to a high degree. In this connection, the record cards must be of substantially uniform thickness as the feeding mechanism which comprises a card picker must pick one card at a time from the supply stack. Also the card is fed through a throat or slot which is wider than the thickness of one card but narrower than the thickness of two cards together so that only one card at a time can be fed therethrough. Also, the stock from which the cards are made must be such that the effects of atmospheric conditions are minimized. In other words, the dampness of the atmosphere must not cause the cards to swell or become soft along their edges and thus cause the cards to stick in the throat or become mutilated by either the throat or the feed picker. Also, the stock from which the cards are made must be durable so that the damaging of the edges of the cards, by the card feed mechanisms, etc., is reduced to a minimum. Slight defects in the edges thereof will often result in crumpling of the cards and consequent stoppage of the machine during the transition of the cards from the stack to another position. Also, the stock must be such that it will not warp in varying atmospheric conditions. The stock must also be of such quality that the cards can be handled and fed through the machines a large number of times without being destroyed or so mutilated as to fail to feed properly in the machines. In the Patent No. 2,041,880, dated May 26, 1936, a method for making these cards is disclosed and comprises pasting two or more sheets of paper together so as to produce cards that are so balanced that atmospheric influences have no effects thereon.

A method commonly employed for sensing the perforations comprises running the cards between a row of electric brushes on one side and an electric contact plate or roller on the other. The brushes usually comprise strands of fine wire and a separate brush is associated with each column on the record card. Sensing takes place while the card is in motion. As the card passes under the brushes, wherever a perforation appears in one of the columns, the brush associated with that column will reach through the perforation and engage the contact plate on the other side, thus closing a control electric circuit through a magnet or relay to control the operation of the machine. The location of the perforation in the column represents the value of the entry and also determines the time in the card feeding cycle at which the circuit is closed, and the time at which the circuit is closed determines the control upon the machine. In other words, it determines the value to be added in the accumulating devices or to be printed upon a report sheet.

In the manufacturing of paper, minute particles of foreign substances in the raw materials find their way into the surface of the paper stock and interfere with the accurate operation of the machines under control of the record cards made from such stock. Among these foreign substances are what are called conducting specks. These specks may be minute particles of carbon or coal dust, or metallic or other substances which are capable of acting as conductors for electric current. When the specks reach from one surface of the record card to the other, the electric brushes engaging the surfaces of the card wipe over the specks which also engage the contact plate on the opposite side and this causes closure of the control circuit in the same manner as where the brush reaches through a perforation and engages the contact plate. Thus, a carbon speck in the cards will cause an incorrect entry to be made in the machine.

Other foreign substances which find their way into the paper making material produce what are termed slime spots. These spots which, while they may not act as conductors of electric current, form weak spots in the cards so that the electric brushes in rubbing over the surfaces of the cards, open perforations through the cards and thus effect wrong entries in the record which thereafter produce incorrect operations of the machines.

An object of the present invention is to produce a record card in which defective spots will

have no effect upon the operation of the machines. One method of making such cards is shown in Patent No. 2,041,881.

Another object of the invention is to produce a multi-ply pasted control card with one or both edges more durable than the usual slitter cut edge card described in the aforementioned patents. Such cards may be produced by slitting the paper to be pasted into strips twice the desired width of the control card and folding in such a manner that the cut edges meet along the central portion of the card. The long edges of the finished card have no cut edges since they are formed by the folds in the paper. In this manner, smooth edges difficult to fray are thus produced.

Cards may be produced by the following methods involving this principle:

1. With two folds forming the long edges and the cut edges of the original paper stock meeting along the central section of the card.

(a) The cut edges may form a straight line along a longitudinal line of the card.

(b) The cut edges may be indented either in a symmetrical or unsymmetrical manner, and formed so as to correspond, which may be fitted or locked together, and not form a line of weakness along the longitudinal line of the card.

2. With one fold forming one long edge of the card and the cut edges of the paper meeting at the other long edge.

3. With a core of inexpensive paper, enclosed in a sheath made of a higher quality of paper folded in the manner described in (1). The finished card made in this manner would be three ply with both long edges formed from folds in the outer sheath of paper.

The advantages of this type of card construction are, briefly, more durable edges, possibility of using cheaper paper, freedom from conducting particles extending completely through the card, and uniformity of the two surfaces providing freedom from warping tendencies.

Various other objects and advantages of the invention will be obvious from the following particular description of one form of mechanism embodying the invention or from an inspection of the accompanying drawings; and the invention also constitutes certain new and useful features of construction and combination of parts herein-after set forth and claimed.

In the drawings:

Fig. 1 is a plan view of a strip of paper from which the cards may be formed.

Fig. 2 is a view to show how the folded edges are formed.

Fig. 3 is a view illustrating one form of finished record card printed and punched, ready to use to control the operations of statistical machines.

Figs. 4, 5 and 8 illustrate other forms of record cards embodying the principle of the present invention.

Figs. 6 and 7 illustrate still another form of record card formed by using a core and outer sheath of paper.

Fig. 9 illustrates a finished record card of the type well known at present, printed and punched for use and illustrating carbon specks and slime spots.

Fig. 10 is a sectional view of a type of card feeding mechanism.

Fig. 11 illustrates a control card being sensed in a calculating machine.

In Fig. 1 the card stock 1 is shown and comprises a sheet of paper, the width (a) of which is

twice the width of a control card to be formed. The edges 2 and 3 are indented or formed in an irregular manner and in such a manner so as to correspond so that edge 3 is adapted to fit into edge 2 so as to be interlocked. In Fig. 2 it is shown how certain sections of the strip 1 are folded to form the long uncut edges 4 and 5 of the control cards. Suitable adhesive 6 is applied to the paper as shown so that as the portions of the paper are completely folded over so that the cut edges 2 and 3 meet the integral sections thereof are glued together. The cut edges meet along a longitudinal line of the control card indicated as 7 in Fig. 3 which in the figure as shown is not a straight line. The juncture or line where the edges are joined or united is irregular so as not to produce a line of weakness along the longitudinal line of union. The juncture as shown may be effected along the central line of the card or along any desired line along one side of the card. Also the edges as shown are formed symmetrically; however, it is not desired to be limited to this identical formation, for it is obvious that the edges can be cut in unsymmetrical formations or indentures. Fig. 3 shows a complete card 8 with control perforations 9 located in the various columns at different index point positions to represent different values. These perforations serve to control the operation of the calculating or other machines.

Referring to Fig. 10, reference numeral 10 designates a stack of perforated control cards 10—a as shown in Fig. 9, from which the cards are picked off one by one by the usual card picker 11 which feeds a card through the throat 12 to the transport rolls 13. The picker 11 is moved or positioned to and fro in the usual way by means of a lever 14 pivoted upon shaft 15 and moved through connecting link 16 by a disk 17 which is operated by suitable means, such as a motor (not shown).

As the control card passes between the sensing brush 18 and the contact roller 19 (also see Fig. 11), it will readily be seen that when one of the perforations 20 passes between the brush and contact roller, a circuit will be closed through the source 21 and operating magnet or relay 22. The energization of the said magnet will control the operation of the machine according to the location of the perforation, in a manner well known and as disclosed in Patent No. 1,976,617.

It will readily be seen that if a speck of carbon dust 23 (Fig. 9) is embedded in the control card and exposed at both surfaces thereof, the brush 18 will contact the speck on the upper surface 25 while the roller 19 will contact it on the lower surface and the operating circuit will be closed through the magnet 22. If the carbon speck is located, as shown in Fig. 9, somewhere between the index point positions five and six, the machine 20 will be caused to accumulate the value five or six and also would be the cause to print one or the other of these erroneous values.

When the card is made up as described in accordance with the present invention, the specks 25 such as shown at 23 may appear on one side of the control card but will be covered over by the other side of the card and thus be prevented from serving as conductors between the brush 18 and roller 19.

A slime spot is indicated at 24 (Fig. 9) at the index position representing the value one. It will readily be seen that as the control card is passing under the brush 18 this weakened spot is likely to loosen and eventually form a hole through the 75

card after a number of passages through the machine, so that thereafter the brush 18 will form a contact at this point and cause erroneous operation of the machine.

5 At 25 a faint speck is indicated to represent a conducting particle covered by pulp fibres. On passing through a testing machine having a row of sensing brushes similar to brush 18 the speck will not be detected due to the layers of pulp fibres. Paper stock having these hidden specks will thus eventually find their way into the statistical machines as control cards and the brushes 18 in such machines will eventually scrape the pulp fibres off the hidden speck and thereafter close the control circuit between the brushes 18 and contact roller 19 to bring about energization of the control magnet 22.

It will be seen that by glueing the sections of the paper stock 1 together as described in conjunction with Figs. 2 and 3 to produce the completed control card 8, all of the mentioned defective spots are rendered harmless and ineffective. Also, it will be seen that the edges 4 and 5 formed by the folds of the paper stock 1 will produce 25 more durable edges than the slit or cut edges on the control cards used at present, so as not to be effected by the numerous passages through the machine.

In Fig. 4 it is shown that in some cases the edges 26 and 27 of the paper stock 28 may be cut in a straight line and folded so that the long edges of the cards are formed by the folded portions of the paper stock and pasted together by the adhesive 29 to produce the completed card 30 as shown in Fig. 5. In Fig. 8 only one edge 31 is formed by the folded portions of the paper stock 32. In Figs. 6 and 7 an inner core or strip of paper stock 33 may be pasted to a portion of the paper stock 35 comprising a sheath which may be

made of a higher quality of paper, the edges 37 and 38 of which may be cut as described hereinbefore, and folded in the manner in accordance with the principles of the present invention to form a multi-ply control card comprising at least 5 three plies and one in which the long edges are formed from folds in the outer sheath of paper. Thus it is seen that in all the examples set forth, smooth, uncut edges for control cards may be formed and which have been found to be more 10 durable and more difficult to fray, in this manner, imparting longer life to the control cards, making it possible to use cheaper grades of paper, creating freedom from foreign or conducting particles, and uniformity of the two formed surfaces. 15

While there has been shown and described and pointed out the fundamental novel features of the invention as applied to a single modification, it will be understood that various omissions and substitutions and changes in the form and 20 details of the device illustrated and in its operation may be made by those skilled in the art without departing from the spirit of the invention. It is the intention therefore to be limited only as indicated by the scope of the following 25 claim.

What is claimed is as follows:

A control card blank for use in record card controlled statistical machines comprising a sheet of imperforate material having serrated edges, 30 said sheet being folded in along two lines disposed parallel to one another to form a card of uniform thickness, the longitudinal edges of said card being formed by the folds of the sheet, and the said serrated edges of the sheet when folded in 35 and secured interlacing one another on one side of the said card.

HARRY O. GEORGE.
